UNITED STATES PATENT OFFICE.

OSCAR VON MORSTEIN, OF SCHOENBERG, GERMANY.

DEVICE FOR ELECTRICALLY LIGHTING OR EXTINGUISHING GAS-JETS.

SPECIFICATION forming part of Letters Patent No. 629,803, dated August 1, 1899.

Application filed February 17, 1896. Serial No. 579,635. (No model.)

To all whom it may concern:

Be it known that I, OSCAR VON MORSTEIN, a subject of the King of Prussia, German Emperor, and a resident of the village of Schoenberg, near the city of Berlin, in the Kingdom of Prussia, Germany, have invented a certain new and useful Device for Electrically Lighting and Extinguishing any Desirable Number of Gas-Jets, (for which I have obtained a patent in Germany, No. 83,344, bearing date June 1, 1894; in Belgium, No. 114,459, bearing date March 5, 1895; in Great Britain, No. 4,670, bearing date March 5, 1895, and in France, No. 245,554, bearing date March 5, 1895;) and I do hereby declare that the following is a full, clear, and exact description of the invention, which will enable others skilled in the art to which it appertains to make and use the same.

This invention relates to a device for electrically lighting and extinguishing any desirable number of gas-jets simultaneously from a distance.

The invention has for its object to provide means for lighting and extinguishing any desirable number of gas-jets simultaneously with the use of only one conductor and one contact. This object is attained, mainly, by means of an electromagnetic gas-pipe-closure opener common to all the gas-jets and which may be applied at any part of the common gas-pipe and of a spark-inductor in which are produced the secondary currents requisite for the ignition of the gas-jets.

The device of the invention is illustrated diagrammatically in the accompanying drawings, in which—

Figure 1 is an elevation of the device with the primary bobbin of the inductor connected with the opening-electromagnet in series; Fig. 2, an elevation with the primary bobbin of the inductor connected with the opening-electromagnet in parallel. Figs. 3^a and 3^b show a modification of the movable pipe-closing part, the latter shown in different positions for the supplementary cutting out of the opening-electromagnet. Figs. 4^a and 4^b show in different positions a further modification of the movable gas-pipe-closing part for the supplementary cutting out of the opening-electromagnet in conjunction with the supplementary connection of the primary bob-

bin of the inductor. Fig. 5 is an elevation of the device with a secondary bobbin consisting of a number of small bobbins. Figs. 6^a 55 and 6^b show in different positions the circuit-breaking arrangement in which the secondary bobbin is distributed on several primary bobbins.

R is the gas-supply pipe, which may serve 60 as the conductor both for the battery-current and for the secondary currents, as is supposed to be the case in all the figures. H is the closing part of said pipe—a cock or a slide, for example; E, the opening-electromagnet; 65 P, the primary bobbin, and S the secondary bobbin, both together forming the inductor I; A, the armature of the electromagnet E; a b, the circuit-breaking arrangement; K, the tin-foil condenser; B, the battery; C, the contact. 70

Both apparatus—namely, the gas-pipe opener E and the inductor I—are in the most intimate connection with each other, both being set in action by the same battery-current, the same conductor, and the same contact. 75 The same current, namely, which excites the opening-electromagnet E produces in the secondary bobbin S the secondary currents required for the ignition of the gas-jets by means of springing sparks. This may be accomplished so that the primary bobbin P of the inductor I, with the opening-electromagnet E, will appear as connected in series or in parallel, Figs. 1 and 2. In Fig. 2 the circuit-breaking arrangement a b is applied to the inductor I and in Fig. 1 to the opening-electromagnet E in such manner that after opening the cock H by the attraction of the armature A and turning of said cock by the armature coming against the stud s said armature 80 in being further attracted, Fig. 1, lifts off the spring contact-piece a from the firm contact-piece b, and in this way short vibrations and current interruptions are produced.

In order not to weaken the induction action 95 of the primary bobbin P by a high resistance in the primary-current circuit, as is the case in Figs. 1 and 2, the displacement of the movable closing part—for example, the plug H of a cock—may be utilized for automatically placing out of circuit the opening-electromagnet E after the opening of the pipe-closure has been accomplished, so that then the battery-current either wholly or for the greater

part passes through the primary bobbin P of the inductor, Figs. 3^a and 3^b. To this end a contact-piece h is provided on the movable part of the gas-pipe closure, say the cock H, which contact-piece comes in contact with the spring e, leading to the electromagnet E, when the cock is fully opened. Of the two bobbins E and P, previously connected in series, E is then short-circuited—that is to say, cut out— and the current passes through P only. Still further and in the same way the primary bobbin P of the inductor I may, after the cock has been opened, be automatically placed in the circuit, Figs. 4^a and 4^b. In this arrangement the two bobbins E P are situated in parallel circuits and each bobbin is in connection on the one hand with a contact-piece e' and on the other hand with a contact-piece p. First the contact-surface h' of the pipe-closure II comes in contact with e', so that the electromagnet E, with the circuit closed, opens the cock H. Then, however, the contact between h' and e' ceases and h' comes in contact with p, so that the current then passes through P only.

As the secondary currents for the ignition of a large number of gas-jets must have a comparatively high tension, and thereby, owing to the difficulty of the insulated passage of the same to and especially at the burners, a limit would have to be drawn, it is advantageous to construct the secondary bobbin S in the form of a number of small bobbins S' S² S³, each of low tension and used for the ignition of a small number of jets only. This may be accomplished by placing small bobbins over or against one another or by a corresponding division of the winding of large bobbins, Fig. 5. If the secondary bobbins are distributed upon several primary bobbins P' P², the current-interrupting arrangement may again be designed so

that the battery-current is conducted alternately through two groups of the primary bobbins. Figs. 6^a and 6^b show such a design of the current-interrupting arrangement in which the spring contact-piece a', after it has been drawn from the fixed contact-piece b', comes against a third contact-piece c, and thus conducts through the bobbin P² the current which is interrupted in the bobbin P'. In a manner analogous to that here given for two primary bobbins the arrangement may also be employed for conducting the current alternately through the opening-electromagnet E and the primary bobbin.

The electromagnetic opening and shutting off of the gas-pipe R is effected in any one of the known ways. In Fig. 1 a second electromagnet Z for closing the gas-pipe R is shown in dotted lines with a second conductor.

What I claim as my invention, and desire to secure by Letters Patent, is—

A device for electrically lighting and extinguishing any desirable number of gas-jets simultaneously consisting in a combination of an electromagnetic gas-closure opener common to all the burners with a device for producing secondary currents composed of a primary bobbin, a secondary bobbin and a circuit-breaker with condenser, with a contact device provided on the gas-closure opener arranged to disconnect from the circuit the electromagnet of the gas-closure opener and at the same time increase the inductor-current, substantially as described.

In testimony whereof I sign this specification in the presence of two subscribing witnesses.

OSCAR VON MORSTEIN.
